UNITED STATES PATENT OFFICE.

HENRY H. SCHMIDT, OF BESSIE, OKLAHOMA.

BENCH-VISE.

1,111,185.

Specification of Letters Patent. Patented Sept. 22, 1914.

Application filed December 9, 1913. Serial No. 805,596.

To all whom it may concern:

Be it known that I, HENRY H. SCHMIDT, a citizen of the United States, residing at Bessie, in the county of Washita and State 5 of Oklahoma, have invented new and useful Improvements in Bench-Vises, of which the following is a specification.

This invention has reference to improvements in vises and more particularly to that 10 class of such devices which are especially designed for use in connection with a carpenter's work-bench.

The object of the invention is to provide means for quickly adjusting the vise to the 15 size of the material desired to be clamped thereby; and, at the same time, to insure a perfect holding of the material at all its points thereon.

A further object is to equally distribute 20 the strain of the clamping member over all portions of the material secured by the vise thereby avoiding a mutilation of the surface of the material, a defect not uncommon with vises where the strain occurs at the top of 25 the clamping member, and one especially noticeable when it is desired to work with soft or spongy lumber such as bass-wood, white-pine, or the like. This equal distribution of the strain of the clamping member 30 upon the material will prevent the same from falling out of the vise into the operating parts beneath when heavy pressure exerted by the tools is applied from above, thereby avoiding the annoyance occasioned 35 the workmen by this, and the consequent loss of time.

A further object is to provide means for quickly throwing and maintaining the vise in open position when the work has been 40 completed without destroying the adjustment for a given size of material.

The invention consists in the construction, arrangement and combination of parts hereinafter more fully described in a preferred 45 form, reference now being made to the accompanying drawing, in which,

Figure 1 is a side elevation of the improved vise; Fig. 2 is a view partly in cross-section and partly in elevation to show the 50 means for operating the vise; and, Fig. 3 is a detail of the means for retaining the vise in a given position.

Like characters of reference refer to like parts throughout the several views.

As shown, the frame of the work bench is indicated at 1 to the end of which is secured

the vise as is generally the custom. A vertical beam 2 formed integral with the work-bench frame forms the fixed standard or jaw of the vise. Midway between the top 60 and bottom of the end of the work-bench frame is a transverse brace 3 to which is secured the strap 4, the purpose of which will be hereinafter described. The movable jaw 5 is provided at its lower portion with a 65 draw-bar 6 formed with a series of notches 7 which form seats for the plate 8 secured to the fixed jaw 2 and extending outwardly therefrom. Fulcrumed in the strap 4 is an L-shaped lever 9 near the upper portion of 70 which is pivoted the looped member 10 which is provided at the upper portion thereof with a removable pin 11. A draw-bar 12 extends through the looped member 10 and is provided with a series of notches 75 13 which coöperate with the upper end of the L-shaped lever 9 to move the said draw-bar laterally. Passed through the outer end of the draw-bar 12 is a pin 14 which is secured to the outer face of the jaw 5 to move 80 the same inwardly during the operation of the lever 9. Pivoted at the lower portion of the said lever 9 is a link 15 which is secured to the treadle-lever 16 mounted for pivotal movement on a pivot pin 16' carried 85 by a bracket 17 secured to the work-bench frame. A looped guide-way 18 fastened in any suitable manner on the inner face of the fixed jaw 2 prevents the outward displacement of the treadle-lever. Adjacent to the 90 forward end of the said lever 16 is provided a spur or tooth 19 which coöperates with a rack 20 secured to the standard 2. In order to maintain the vise in normally open position a spring 21 is secured at one end to 95 the upper portion of the work-bench frame and at the other to a link 22 which is in turn fastened to the treadle lever 16. It will be seen that by the operation of the treadle-lever 16 the dog 19 is disengaged from the 100 rack 20 the tension of the spring on the lever 16 will cause the same to move upwardly and throw open the vise.

The operation of the device is as follows:—The material having been placed in 105 the space between the standard 2 and movable jaw 5 pressure is applied on the treadle-lever 16 thereby moving the L-shaped lever 9 on its pivot which causes its upper portion which is in engagement with 110 one of the teeth of the draw-bar 12 to pull the same inwardly carrying with it the mov-

able jaw 5 and clamping the same against the material. When the work has been completed and it is desired to open the vise the spur or tooth 19 is disengaged from the rack 5 20 and the pressure of the foot is released from the treadle-lever allowing the spring 21 to exert its upward pull on the treadle-lever 16 causing the link 15 to move the L-shaped lever 9 in a reverse direction, there- 10 by throwing out the draw-bar 12, and releasing the pressure of the pin 14 on the movable jaw. It will then be easy to remove the material from the vise. By removing the pin 11 from the L-shaped member 10 the 15 draw-bar 12 may be moved freely therein for any given adjustment. It will be noted that the vise is also capable of adjustment at its bottom portion thereof by means of a series of notches on the draw-bar 6, the en- 20 gagement of which with the plate 8 may be varied at will to suit the size of the material.

By this double adjustment of the vise, the movable jaw is always maintained in a substantially vertical position even when engag- 25 gaging the material in its closed position. It will thus be seen that by reason of this the strain is equally distributed along the entire surface of the movable jaw insuring a like and equal distribution of the strain 30 on the material clamped, thereby preventing the same from mutilation by the movable jaw, and at the same time, holding the material firmly in the vise.

What I claim is:—

35 1. A vise comprising, in combination, a fixed jaw and a movable jaw, a lever, a looped guide pivoted to one end of said lever, a draw-bar in said guide and engaging said end of the lever, a pin on said draw- 40 bar bearing against the outer surface of said

movable jaw, and means on the other end of said lever for turning the same whereby to reciprocate said draw-bar and cause the pin carried thereby to exert pressure on the movable jaw to close the vise. 45

2. In a vise having a frame with a fixed jaw, and a movable jaw, upper and lower draw-bars carried by the movable jaw and having notches in their lower edges, a plate carried by the fixed jaw having an opening therethrough for the reception of said lower draw-bar and with which said notches are adapted to engage whereby to adjust the draw-bar, a lever pivoted on said frame having one end engaging the notches of the upper draw-bar, a yoke carried by the lever receiving the inner end of the upper draw-bar, and means for reciprocating said lever whereby to move said upper draw-bar to open and close the vise. 55 60

3. In a vise having a frame with a fixed jaw and a movable jaw, means for adjustably and pivotally connecting the lower ends of said fixed and movable jaws, a draw-bar carried upon the upper end of said movable jaw, a lever supported on the fixed jaw, a yoke carried upon the lever engag- 65 ing the draw-bar to adjustably and pivot- ally secure the draw-bar to the lever, and means for reciprocating the lever to move 70 said draw-bar whereby to open and close the movable jaw.

In testimony whereof I have hereunto set my hand in presence of two subscribing wit- nesses.

HENRY H. SCHMIDT.
